UNITED STATES PATENT OFFICE.

FRITZ ECKEY, OF TWICKENHAM, ENGLAND.

SASH RAISING AND LOWERING DEVICE.

1,109,326.

Specification of Letters Patent.

Patented Sept. 1, 1914.

Application filed March 14, 1914. Serial No. 824,727.

To all whom it may concern:

Be it known that I, FRITZ ECKEY, a subject of the King of Prussia, residing at Twickenham, England, (whose post-office address is 21 Sidney road, St. Margaret's, Twickenham, Middlesex, England,) have invented certain new and useful Improvements in Sash Raising and Lowering Devices; and I do hereby declare the following to be a full, clear, and exact description of the invention, such as will enable others skilled in the art to which it appertains to make and use the same.

This invention consists of improvements in and relating to sliding windows such as those employed in motor cars, railway carriages, and like sliding windows, and particularly the invention consists in improvements in lazy tongs apparatus or mechanism 20 for raising and lowering such windows.

Heretofore lazy tongs apparatus has been proposed, for raising and lowering railway and other carriage windows, in which the lowermost members or levers of the lazy tongs have been fitted to a suitable base plate and said levers connected to a suitable balancing spring or springs the said base plate and springs being mounted at or adjacent to the bottom of the window well in the door or wall of the vehicle, the window glass being mounted on the uppermost members or levers of the lazy tongs. In some of such proposed arrangements an operating handle or knob was provided on the window glass itself, or on the sash in which the window glass is mounted, so that on moving the window up and down by means of such knob or handle the lazy tongs was respectively opened or expanded and closed or collapsed. In other proposed arrangements an operating handle or lever with a connection or connections to the lazy tongs was provided so that by actuating such handle or lever the lazy tongs was opened or expanded and closed or collapsed respectively for raising and lowering the window, and further means were provided in connection with such operating handle for locking or holding the window in the desired position for instance either fully open or fully closed, or partially closed and in one such construction it was proposed to pivotally mount a pair of levers on a bar midway between the bottom of the door and the lock rail and to connect the lower ends of such levers to the lower members of the lazy tongs and the upper ends to

the said operating lever or handle. Such previously proposed constructions and arrangements are, however, objectionable in several respects. For instance the pivoting of the lowermost levers or members of the lazy tongs on a base plate at the bottom of the window well in the door or wall of the vehicle renders it a matter of considerable difficulty and increased cost for fitting up 60 the apparatus and especially so in the case of applying such apparatus to existing vehicles. Further the apparatus is difficult of access should repair be necessary. Another objection to such previously proposed apparatus is that the window glass,—or the sash in which the window glass is mounted,—being connected to the uppermost members or levers of the lazy tongs, the said lazy tongs occupies so much space in the bottom of the 65 well down into which the window slides as to prevent the window being completely opened so that there is always a portion of the window glass or of both the window glass and the sash in which it is mounted 70 projecting above the top of the well or above the lock rail at the bottom of the aperture which is to be closed by the window.

The apparatus according to the present invention has been designed to overcome the 75 above mentioned objections as well as other objections incidental to the construction and arrangement of the previously proposed mechanism.

The present invention therefore consists 80 principally in a construction and arrangement of lazy tongs apparatus such that the window glass, or the sash in which the window glass is fixed, is mounted at or adjacent to the lower end or on the lowermost 85 members or levers of the lazy tongs, while the top or uppermost members of the lazy tongs is or are mounted at or adjacent to the top of the window well in the door or wall of the vehicle, so that when the window is moved downwardly to its open position the lazy tongs is opened or expanded and on the other hand when the window is moved to its closed position the lazy tongs is closed or collapsed.

The present invention also comprises an 90 improved construction and arrangement of gear or mechanism in conjunction with an operating handle for closing or collapsing 95 and opening or expanding the lazy tongs 100 so as to respectively close and open the window, the said mechanism being also mounted 105

at or adjacent to the top of the window well in the door or wall of the vehicle.

Further in the construction of the apparatus according to this invention there is 5 provided and mounted at the lower end of the main lazy tongs a secondary or smaller lazy tongs on whose upper levers or members the window glass,—or the lower transverse member of the sash in which the window glass is fitted,—is mounted, this smaller 10 lazy tongs being so operatively connected with the main lazy tongs that when the latter is closed or collapsed for the purpose of raising or closing the window the smaller 15 lazy tongs is opened or expanded while when the main lazy tongs is opened or expanded, for lowering or opening the window, the said smaller lazy tongs is closed or collapsed. Suitable spring balancing means 20 is also preferably provided. The lazy tongs apparatus itself may be also conveniently mounted on the said lock rail at or adjacent to the top of the window well. The gear or mechanism for actuating the lazy tongs comprises 25 a pair of toothed wheels or sprocket wheels one of which is arranged so as to be rotatable by a suitable operating handle provided for actuating the lazy tongs so as to open and close the window, while the other 30 sprocket wheel is rotatable on a suitable pivot or spindle and acts as a guide wheel for a suitable endless chain (which may be of the kind usually employed for driving cycles) which works on the said sprocket 35 wheels, the said chain being operatively connected with the lazy tongs by means of a spindle or other suitable means.

Further, locking mechanism is provided 40 for locking or holding the operating handle of the lazy tongs apparatus in any desired position, thus also locking or holding the window in the desired position, the said locking means being such that a preliminary movement of the operating handle actuates a 45 lock or catch so as to release or unlock the handle of the lazy tongs, while another movement of the operating handle will actuate the lazy tongs apparatus so as to open or close the window according to the direction 50 of movement of the handle, and another movement of the said operating handle will cause or permit the lock to catch to be actuated so as to again lock the handle of the lazy tongs and consequently hold the 55 window in the desired position.

Further features of the invention and details of construction will appear from the following description with reference to the accompanying drawing which illustrate 60 application according to this invention.

In these drawings: Figure 1 is an elevation of the apparatus showing the main lazy tongs fully closed or collapsed and the smaller or secondary lazy tongs fully open 65 or expanded this being the position of the

parts when the window is completely closed. Fig. 2 is a similar view to Fig. 1 but shows the main lazy tongs fully open or expanded and the smaller or secondary lazy tongs fully closed or collapsed, this being the position of the parts when the window is completely lowered into the well, *i. e.* when the window is fully down or open. Fig. 3 is an elevation showing the hereinbefore mentioned toothed or sprocket wheels and the 70 endless chain engaging therewith, the casing or housing which incloses said sprocket wheels and chain being omitted. Figs. 4 and 5 are respectively elevation and side view of the casing or housing which incloses the sprocket wheels and chain, hereinafter more fully described. Fig. 6 is an elevation of a plate on which the various parts of the apparatus are mounted. Figs. 7 and 8 are 75 respectively top plan and transverse sectional views of the casing or housing referred to in the description of Figs. 4 and 5. Fig. 9 is a side elevation partly in section of the apparatus with the parts in the position shown in Fig. 2. Figs. 10 and 11 are side 80 elevations partly in section of the operating handle and the locking means operatively connected therewith as hereinafter described. Fig. 12 is an elevation, looking in the direction of the arrows, Figs. 10 and 11, the operating handle being omitted. Figs. 13 and 14 are respectively front and side 85 views of a portion of the sprocket chain showing means by which the chain is operatively connected to the main lazy tongs as hereinafter described. Figs. 15 and 16 are 90 elevations showing the apparatus applied to the window of a railway carriage door. Fig. 15 showing the window completely closed and Fig. 16 showing the window partly 95 open. Fig. 17 is a plan view showing the method of mounting the apparatus on the cross-bar or "lock rail" at the top of the window well in the door of a railway or other vehicle.

Like reference numbers indicate corresponding parts in the various figures of the drawings.

Referring first to Figs. 1 to 8 of the drawings, 1, 1^a are the uppermost members or levers, 2, 2^a the lowermost members or levers and 3, 3^a intermediate members or levers of the main lazy tongs, the said intermediate members or levers being pivotally connected (in the known or any convenient manner) at their ends to the uppermost and lowermost levers or members as clearly shown in the drawings. The uppermost levers or members 1, 1^a are rotatably mounted at their inner ends on the pins or pivots 4, 4^a which in the example shown are secured to the casing or housing 5 which is suitably secured to a plate 6 adapted to be secured, for instance by means of screws through the flange 6^a, to a suitable support at or adjacent to the 110

top of the well or recess, in the door or structure, into which the window slides when opened. As shown, the housing or casing 5 is secured to the plate 6 by screws passing through flanges 7 and 8 on the housing 5 which may be a casting or may be made of sheet metal suitably cut and pressed to the desired form. The hereinbefore mentioned secondary or smaller lazy tongs comprises lower members or levers 9, 9^a and upper members or levers 10, 10^a, the lower ends of the levers, 9, 9^a being suitably secured to the lowermost members or levers, 2, 2^a of the main lazy tongs, for instance, as shown, the lower ends of the levers 9, 9^a of the smaller lazy tongs are fixed respectively to the lower end of the relatively short arms or plates 11, 11^a the opposite ends of which are suitably fixed to the lower members or levers 2, 2^a of the main lazy tongs; the upper end of lever 9 is pivotally connected at 12 to the lower or outer end of lever 10, and the upper end of lever 9^a is pivotally connected at 13 to the lower or outer end of lever 10^a. The upper or inner ends of levers 10 and 10^a are pivotally connected together and have mounted on them a suitable device by means of which the bottom of the window glass, or the bottom of the sash in which the window glass is mounted, can be attached to the levers or members 10, 10^a of the smaller lazy tongs. In the example shown, a bifurcated bracket or clip 14 is pivotally mounted on the pin or pivot 15 that connects the upper or inner ends of levers 10, 10^a, the said bracket 14 having a projecting lug 16 by means of which the window is attached to the smaller lazy tongs; the lug 16 engages between depending lugs on a suitable part 17 (Fig. 15) secured to the bottom of the window glass or to the bottom of the sash in which the window glass is fitted, a transverse pin being passed through said lugs and the lug 16. 18 is the pin pivotally connecting the lowermost members or levers 2, 2^a of the main lazy tongs together, and also pivotally connecting, at a position intermediate to their ends, the lower members or levers 9, 9^a of the smaller or secondary lazy tongs. 19 (see Fig. 9) being a sleeve or ferrule on the pin 18 and between the levers 2, 2^a of the main lazy tongs and the levers 9, 9^a of the smaller lazy tongs. 20 is a pin or pivot which operatively connects the intermediate levers or members, 3, 3^a of the main lazy tongs to the sprocket chain 21, the said pin 20 being as shown (more clearly in Figs. 13 and 14) provided or formed on a plate or bar 21 which at each end is mounted on extensions of pivot pins 21^a, 21^b that serve for connecting links of the chain 22 together. As clearly shown the pin 20 projects through holes provided centrally in the intermediate levers or members 3, 3^a of the main lazy tongs which levers may be

held in engagement with the pivot 20 in any suitable manner for instance by means of a split pin passing through the pin or pivot 20. 23 and 24 (see Figs. 3 and 9) are the hereinbefore mentioned sprocket wheels on 70 which the chain 22 works, 23 being the driving wheel through which movement is given to the chain 22, and, through the said chain and pin 20, to the lazy tongs apparatus. As clearly shown in Fig. 9 the sprocket wheel 23 has tubular bosses which bear and revolve in opposite holes one of which is provided in the plate 6 and the other in the housing or casing 5, and the sprocket wheel 24 is rotatably mounted on a pivot or pin 25 the 80 opposite ends of which are preferably fixed respectively in the plate 6 and housing or casing 5.

26 (see Figs. 1; 2 and 4) is a slot in the casing 5 through which the hereinbefore mentioned pin 20 projects and in which the said pin moves up and down as the chain 22 is actuated for raising and lowering the window.

27 (Figs. 7 and 8) are strips of leather or other suitable soft material arranged along the sides of the casing or housing 5 for the purpose of preventing objectionable noise which would occur if the chain 22 could work against or come in contact with the 95 metal housing 5.

Referring now to the handle for actuating the lazy tongs apparatus and the means for locking or holding said apparatus and the window in the desired position, 28 is a handle which is pivotally connected to the outer end of a spindle 29. The handle 28 as shown is of T shape but may of course be of any other suitable shape. Further, in the example shown, the inner end of the handle 28 is 105 bifurcated so as to take on either side of the outer end of the spindle 29 to which the handle is pivotally connected, for instance by a suitable pin 30, the spindle 29 as shown having a cross head 31, the arrangement being such that the handle 28 can be turned on the pivot 30 from the position shown in Fig. 10 down to the position shown in Fig. 11, or the handle 28 might be turned upward to the opposite position to that shown in 115 Fig. 11.

32 is a casing or housing, which may be a casting, adapted to be secured to the front or outside of the plate 6; for instance the casing 32 may have lugs 33 provided on it whereby 120 the said casing may be screwed on to the plate 6. Within the casing 32 is a disk 34 having three or any suitable number of dowel pins or projections 35 formed or provided on its inner face the said disk 34 being 125 capable of sliding inwardly and outwardly in the casing 32.

36 is a hole bored centrally through the disk 34, and 37 is a spring which at one end bears on the outer face of the disk 34 and at 130

- its other end bears against the outer or front wall of the casing 32, the said spring tending to press the disk 34 upwardly from the position shown in Fig. 10 to the position shown in Fig. 11. The disk 34 is secured on the square portion 29^a of the spindle 29 by suitable means, such for instance as a cross pin 30^a in the spindle which projects through the hole 36 in the disk 34.
- 16 As clearly shown in Figs. 9, 10 and 11 the part 29^a of the spindle 29 is rectangular in form, or of other suitable shape, adapted to engage in the correspondingly shaped hole extending through the sprocket wheel 23 and
- 15 through the bosses of the said wheel, so that when the handle 28 is turned the spindle 29 will, through its rectangular or other suitably shaped part, revolve the sprocket wheel 23 and so transmit motion to the chain 22.
- 20 38 (Fig. 6) is an annular series of holes in the plate 6 with which the pins or projections 35 on the disk 34 are adapted to engage, 39 being a hole in the plate 6 in which one boss of the sprocket wheel 23 engages and
- 25 rotates. By connecting the inner ends of the uppermost members or levers 1, 1^a of the main lazy tongs to the separate and respective pivots or pins 4, 4^a the overall depth or thickness of the apparatus, as measured from
- 30 front to rear, is reduced to a minimum this being important owing to the confined space in which the apparatus has to be fitted or mounted.
- 35 40 is a known form of flat balancing spring one end of which is coiled and mounted on the plate 41 suitably secured on one of the panels of the door, 42 being the usual roller mounted on the spring 40 and engaging with and working on the lower edge of
- 40 the window or of the sash in which the window glass is mounted. The inner end of the coil of spring 40 is secured to a pin on plate 41.
- 45 The construction of the apparatus is such that it can be very easily and quickly fitted in and removed from its position, for instance in the door of a railway carriage, motor car or other vehicle. As shown in Figs. 15, 16 and 17, the cross bar (known as the
- 50 "garnish rail" or "lock rail") 43, at the top of the well or recess in the door into which the window slides when opened, is cut across the middle so as to provide a space of sufficient size to receive the plate 6, with housing
- 55 5 on which the various parts of the lazy tongs apparatus are mounted, 44 being a steel or other suitable metal plate which is secured, for instance, by means of screws, to the outer face of the lock rail 43 a portion
- 60 60 of this plate 44 being cut away to accommodate the housing or casing 32 inclosing locking mechanism as hereinbefore described. The plate 6 with the various parts attached can then be simply slid downwardly into
- 65 the recess formed by the cut away portion of the lock rail 43 and the plate 44 attached to the said lock rail and the plate 6 is then secured, by two (or if desired more) screws passing through the flange 6^a of the plate, to the top or upper edge of the lock rail 43. Should it be necessary to remove the apparatus, for instance for the purpose of examination or repairs, it is only necessary to remove the two screws from the flange 6^a (the window glass being of course disconnected from the lazy tongs apparatus and removed) when the whole of the apparatus can be very easily removed from the wall or recess in the door.
- As shown in Figs. 1 and 2 the upper end of the arm or plate 11 is secured, for instance, as shown, by rivets, on the outer face or side (relatively to the plate 6) of the lever 2 of the main lazy tongs, the lower end of the said arm 11 being secured to the inner face or side of the lever 9 of the smaller lazy tongs; on the other hand the upper end of the arm or plate 11^a is secured on the inner face or side of the lever 2^a of the main lazy tongs, the lower end of the said arm 11^a being secured to the inner side or face of the lever 9^a of the smaller lazy tongs the said lower end of the arm 11^a being suitably offset or cranked and secured to the end of the lever 9^a. A suitable spacing block or distance piece such as 11^b (Fig. 1) may be interposed between the end of the arm 11^a and the end of the lever 9^a to which the said arm is secured, for the purpose of reducing the cranking or "set" required in arm 11^a. Instead of the lower ends of the arms or plates 11, 11^a being fixed, for instance by means of rivets as shown, to the lower ends of the levers 9, and 9^a respectively of the smaller lazy tongs, the lower ends of the arms 11, 11^a might, if desired, be pivotally connected with the lower ends of the said levers 9 and 9^a respectively.
- With the handle 28 and the disk 32 in the position shown in Figs. 9 and 10 the projections or pins 35 on the disk 34 are out of engagement with the holes 38 in the plate 6, the disk 34 being held, through the medium of the pin 30^a, in the position shown in these figures by the inner end of the handle 28 bearing against the outside of the casing 32 the spring 37 being then compressed. With the parts in this position the handle 28 can be turned in one direction or the other thus, through the squared portion of the spindle 29, revolving the sprocket wheel 23 and actuating the chain 22 so as to collapse or expand (according to the direction in which the handle 28 is turned) the main lazy tongs thus opening or closing the window according to the direction in which the said handle is turned. As hereinbefore mentioned when the main lazy tongs is closed or collapsed, in the action of raising or closing the window, the smaller or secondary

lazy tongs is, through the arms 11 and 11^a connecting the lower levers 9, 9^a of the said smaller lazy tongs to the lowermost levers 2, 2^a of the main lazy tongs, opened or expanded; on the other hand when the main lazy tongs is opened or expanded in the action of lowering or opening the window the smaller lazy tongs is closed or collapsed.

If it is desired to hold or lock the lazy tongs apparatus and consequently the window in any desired position, for instance a partly open position of the window, the handle 28 is turned on the pivot or pin 30 from the position shown in the Figs. 9 and 15 to the position shown in Fig. 11 (or equivalent position) whereupon the spring 37 will expand so as to force the disk 34 outwardly from the position shown in Fig. 10 to the position shown in Fig. 11 in which 20 position of the disk 34 the pins 35 thereon enter holes 38 (Fig. 6) in the plate 6 thus preventing further turning of the handle 28 and so holding the lazy tongs apparatus and the window in the desired position. To again 25 release the handle 28 of the lazy tongs apparatus the said handle is again turned from the position shown in Fig. 11 to the position shown in Fig. 10 (or equivalent position) thus, through the pin 30^a of the spindle 29, 30 drawing the disk 34 inwardly in the casing 32 thereby withdrawing the pins 35 from the holes 38 in the plate 6 and so unlocking the handle 28 of the lazy tongs apparatus which may then be again actuated for opening 35 or closing the window.

Variations in and departures from the particular details of construction of certain parts of the apparatus as shown in the drawings might be made without departing from 40 the main features of the invention. For instance in place of the sprocket wheels 23 and 24 and chain 22 some other suitable means might be employed for actuating the lazy tongs; also some other suitable means 45 for holding or locking the lazy tongs apparatus and the window in the desired position might be employed. Nevertheless I wish it to be understood that the mechanism for actuating the lazy tongs apparatus and for locking or holding the said apparatus and the window in the desired position as hereinbefore described and shown in the drawings has been proved in actual practice to be highly efficient and satisfactory.

55 What I claim as my invention and desire to secure by Letters Patent is:—

1. In a device for raising and lowering windows, the combination, with a stationary support, and a main lazy tongs having its 60 upper end levers connected to the said support; of a secondary lazy tongs working in the reverse direction from the main lazy tongs and having its lower end levers operatively connected with the lower end 65 levers of the main lazy tongs, means

for connecting the upper end levers of the secondary lazy tongs with the window, and means for operating both the lazy tongs connected to the intermediate levers of the said main lazy tongs.

2. In a device for raising and lowering windows, the combination, with a stationary support provided with a locking device, and a lazy tongs apparatus connected to the support and adapted to actuate a window; 70 of drive wheels journaled in the support, a flexible driving device passing over the said wheels and operatively connected with the lazy tongs apparatus, a housing secured to the said support, an operating shaft slideable longitudinally in the housing and in one of the drive wheels and adapted to revolve the latter, a spring-pressed locking-plate mounted to revolve with the operating shaft and arranged to slide into and out of 75 engagement with the said locking device, and a handle pivoted to the said operating shaft outside the housing and adapted to revolve the shaft when placed axially in line with it, said handle having a projection 80 which normally holds the locking devices out of engagement with each other and which permits them to interlock when the handle is moved to a position crosswise of 85 the operating shaft.

3. In lazy tongs apparatus for operating sliding windows, the combination with a main lazy tongs adapted to be pivotally mounted at its upper end on a support, a secondary or smaller lazy tongs mounted 90 on the lower end of the said main lazy tongs, means for actuating the main lazy tongs, and means on the secondary lazy tongs for supporting the window or window glass, of a pair of operating members for the secondary lazy tongs, one operating member 95 being fixedly connected to one of the lowermost levers of the main lazy tongs at a point intermediate the pivotal points of said lever and operatively connected to one 100 of the lowermost levers of the secondary lazy tongs below the point of intersection of said levers and the other operating member similarly connected to the other lowermost lever of the main lazy tongs and of 105 the secondary lazy tongs respectively.

4. In apparatus of the kind set forth, comprising a main lazy tongs pivotally mounted at its upper end on a plate and a smaller lazy tongs operatively connected 110 with the lower end of the main lazy tongs, the combination with lower levers of the smaller lazy tongs, which levers cross or intersect each other and at their point of intersection are pivotally mounted on the 115 pivot or pin connecting the inner ends of the lowermost levers of the main lazy tongs, of a pair of arms or plates fixed at their upper ends one on each of the lowermost levers of the main lazy tongs the said arms 120

being fixed at their lower ends respectively one to the lower end of one of the said intersecting levers of the smaller lazy tongs and the other to the lower end of the other 5 intersecting lever of the smaller lazy tongs, and means for actuating (opening or expanding and closing or collapsing) the main lazy tongs, for the purposes set forth.

5. In apparatus, for the purposes set forth, 10 the combination with a main lazy tongs, a smaller lazy tongs operatively connected at the lower end to the lower end of the main lazy tongs, and a plate on which the main lazy tongs is pivotally mounted at its upper 15 end, of a spindle, a sprocket wheel with which the said spindle is in driving connection; a handle in operative connection with the said spindle, a lower sprocket wheel, an endless sprocket chain in operative engagement with the said sprocket wheels, 20 and a pivot pin fixed on the said chain and in operative engagement with intermediate levers or members of the main lazy tongs, substantially as and for the purposes described. 25

6. In lazy tongs apparatus for the pur-

poses set forth and comprising a main lazy tongs and a smaller lazy tongs operatively connected with the lower end of the main lazy tongs, and a plate on which the main 30 lazy tongs is pivotally mounted at its upper end, the combination of a pin or the like in pivotal engagement with intermediate crossed levers or members of the main lazy tongs, and means in connection with the said pin for actuating (opening or expanding and closing or collapsing) the lazy 35 tongs apparatus.

7. A lazy tongs apparatus having its uppermost members or levers pivotally mounted on separate and independent pivots or pins which pivots or pins are themselves mounted on a plate adapted to be secured to a cross bar or support at the top of the recess or well into which the window slides 40 when opened.

In testimony whereof I have affixed my signature, in presence of two witnesses.

FRITZ ECKEY.
